UNITED STATES PATENT OFFICE.

HARRY DUKELSKY, WILLIAM STEIN, AND SAMUEL SCHOENBERG, OF NEW YORK, N. Y.,
ASSIGNORS TO THE YANKEE NEEDLE GUARD CO., INC., OF NEW YORK, N. Y., A
CORPORATION OF NEW YORK.

NEEDLE-GUARD.

1,177,607.

Specification of Letters Patent.

Patented Apr. 4, 1916.

Application filed April 24, 1915. Serial No. 23,566.

To all whom it may concern:

Be it known that we, HARRY DUKELSKY, a citizen of the United States, residing in the city of New York, borough of Manhattan, in the county and State of New York, WILLIAM STEIN, a citizen of the United States, residing in the city of New York, borough of Brooklyn, in the county of Kings and State of New York, and SAMUEL SCHOENBERG, a subject of the Czar of Russia, residing in the city of New York, borough of Brooklyn, in the county of Kings and State of New York, have invented new and useful Improvements in Needle-Guards, 15 of which the following is a specification.

Our invention relates to needle guards, to be used upon sewing machines and other devices using a needle, a small punch or the like, in order to prevent accidental injuries 20 to the fingers of the operator while engaged in handling the cloth or other material operated upon, as the same is fed by hand through the machine.

As used upon sewing machines, our invention 25 may be used upon practically all kinds, whether driven by treadle or by power, and whether the material operated upon be cloth, bagging, carpeting, shoes or stock of any other kind.

More particularly stated, our invention 30 comprehends a guard to be detachably mounted upon the presser bar of the machine, or upon some equivalent part, in close proximity to the needle, and provided with 35 a shield of suitable form for normally preventing the admission of the operator's fingers into the path of travel of the needle, while at the same time enabling the operator to see clearly the portion of the work 40 being operated upon by the needle.

Our invention further contemplates means 45 for enabling the operator to quickly swing the shield to one side, by a movement somewhat resembling that of a swinging gate, in order to promote access to the needle in 50 order to thread the same, or to remove and replace the needle.

Reference is made to the accompanying drawing forming a part of this specification, and in which like letters indicate like 55 parts in all of the figures.

Figure 1 is a fragmentary perspective of a sewing machine equipped with our improved needle guard. Fig. 2 is a plan view 60 of our device, showing in full lines the guard

as it appears when in its normal condition or ready for work, and indicating in dotted lines how the guard is occasionally swung to one side, in order to promote free access to the needle. Fig. 3 is a front elevation of the 60 needle guard, showing the shield as occupying its normal position, in order to protect the operator's fingers. Fig. 4 is a side elevation of the needle guard. Fig. 5 is an enlarged section on the line 5—5 of Fig. 3, 65 locking in the direction of the arrows. Fig. 6 is a front elevation of the guard, showing the shield as swung into its abnormal position in order to facilitate access to the needle and parts adjacent thereto. 70

The sewing machine head appears at 7, the lifter arm at 8, and the pivot bolt for the lifter arm at 9. The needle bar is shown at 10, the needle at 11, the thread at 12, and the thread guide at 13. The bed plate appears at 14, and the throat plate at 15. The presser bar 16 carries the presser foot 17^a and is under control of the lifter arm 8 to the extent that the presser bar and presser foot may be raised and lowered by movements of the lifter arm 8. The presser bar and presser foot are adapted for vertical reciprocating movement well understood in this art. A screw 17 is used for holding the presser foot detachably and adjustably upon 80 the presser bar. The parts thus far described may be of the usual or any preferred construction. 85

We make use of the screw 17 in order to 90 detachably mount our needle guard upon the machine, as may be understood from Fig. 1.

We supply a supporting plate 18, which in this instance is made from a single piece of sheet metal, of double thickness, as indicated in Fig. 5. The supporting plate 18 is provided with a pair of looped portions 20, 21, each having a general form approximating that of a tube, and having more or less resiliency because of their form. These portions 20, 21, because of their shape and purpose, we conveniently designate as a pair of tubular jaws. The supporting plate is further provided with a hole 21 for receiving the screw 17, and with a bearing 22 of tubular form. 95 100 105

Revolubly mounted in the bearing 22 is a stem 23, and the upper part 24 of this stem is bent to a right angle relatively to the axis of the bearing 22. A number of small rods 110

25, 26, 27 are supported by the horizontal portion 24 of the stem, the rods 25, 26 being connected together by shorter rods 28, 29. All of the rods 25, 26, 27, 28 and 29 are 5 in this instance soldered or welded together, and collectively they constitute a shield of reticulate form. The portion 24 has in this instance the form of two rods twisted together, as may be understood from Fig. 5, 10 and this portion is adapted to be forced in between the tubular jaws 19, 20. In practice the jaws snap as the portion 24 of the stem is forced in between them. While the relative movement of the jaws is hardly perceptible to the eye, it is sufficient to bring the jaws slightly nearer to each other whenever the portion 24 is pressed in between them to a sufficient distance—that is, when the portion 24 passes the adjacent centers of contact 15 of the jaws. With the jaws thus gripped, the shield is held firmly and without any lost motion. By a slight pressure of the operator's finger, the portion 24 may be disconnected from the jaws 19, 20, and thus disconnected 20 the shield may be swung around, as indicated by the curved arrow in Fig. 2, and when the limit of travel is thus reached, the parts appear as indicated in Fig. 6. The operator's finger appears at 30. 25

30 The operation of our device is as follows: The parts being assembled and arranged as above described and as shown in Fig. 1, the stock to be operated upon, which as above explained may be cloth or other material, is 30 fed by hand beneath the presser foot 17^a. The operator need not be afraid that the needle will be thrust into his fingers. If he places one of his fingers near the needle, as shown at 30, the finger merely lodges against 35 some one or more of the rods comprising the shield. The operator being thus relieved of the fear of injury to his fingers, can give his entire attention to his work, and in doing this he saves time.

40 45 When the needle is to be threaded, or is to be removed, or replaced, or when the operator wishes to make a close inspection of the condition of the work or of the presser foot, the shield is grasped by hand and turned, as indicated in Figs. 2 and 6, a little pressure being used at the start in order to disengage 45 the jaws 19, 20. When the operator is ready

to proceed with the work, the shield is restored to its position indicated in Fig. 1.

It will thus be observed that our invention 55 serves two general purposes, one being humane and the other economical. A wound inflicted upon the finger by the thrust of a needle is not only painful but dangerous, and a machine operator is liable to waste 60 time in watching his or her fingers in order to keep them out of the path of travel of the needle. By the use of our device these hardships are avoided.

Our invention may be applied to new machines during the manufacture thereof, or 65 may be used as an attachment for machines already in use. In the particular instance here shown the device is used as an attachment for an ordinary sewing machine as 70 used in the factory and household.

The needle guard, when completed, consists practically of only two pieces. It can be manufactured cheaply, and applied to the 75 machine by any person of average intelligence. Its use requires no particular skill or special knowledge.

We do not limit ourselves to the exact construction here shown and described, as variations may be made in the form of the invention. Neither do we limit the device to use upon sewing machines alone, nor to work 80 upon any particular material, the scope of the invention being commensurate with our claim.

85 We claim:—

As an article of manufacture a supporting plate provided with a pair of jaws of sheet metal each having a substantially tubular form and disposed parallel with each 90 other, said jaws being slightly resilient, and a shield journaled upon said supporting plate and provided with a portion to be forced in between said jaws in order to normally hold said shield firmly in a predetermined position relatively to said supporting 95 plate and to permit the swinging of said shield into an abnormal position relatively to said supporting plate.

In testimony whereof, we hereby sign our 100 names.

HARRY DUKELSKY.
WILLIAM STEIN.
SAMUEL SCHOENBERG.
